UNITED STATES PATENT OFFICE.

FRANK H. FRENCH, OF PRESTON, IOWA.

BRUSH OR MOP.

1,113,897.

Specification of Letters Patent. Patented Oct. 13, 1914.

Application filed December 30, 1913. Serial No. 809,536.

To all whom it may concern:

Be it known that I, FRANK H. FRENCH, citizen of the United States, residing at Preston, in the county of Jackson and State of Iowa, have invented certain new and useful Improvements in Brushes or Mops; and I do hereby declare the following to be a full, clear, and exact description of the invention, such as will enable others skilled in the art to which it appertains to make and use the same.

My invention relates to cleaning implements, and more particularly to the class of mops or brushes having oil applied to their fibers so as to render them substantially dustless when used for cleaning and polishing floors and other wood-work.

One object of my invention is to provide simple means for securing the fibers of a mop or brush to a support in such relation thereto as to press the ends of the fibers simultaneously and in substantially a common plane to the floor or other wood-work engaged thereby when the brush is in use.

Other objects are to provide means for distributing oil or polish gradually and fairly uniformly over the fibers comprising the brush or mop, and to provide a cushioning rim to avoid the marring of walls or furniture by contact with the head of the mop.

Further objects will be apparent from the accompanying drawings, in which—

Figure —1— is a fragmentary view, partly in section, showing a mop embodying my invention. Fig. —2— is a plan view of the same with portions of the handle and of the adjoining parts shown in section. Fig. —3— is a fragmentary sectional view through the head of the mop showing an alternative embodiment of my invention.

In the drawings, the mop or brush of my invention consists of a series of fibers or active members 1 strung or looped over an annular member 2, which member preferably consists of a ring having at one edge a pair of parallel arms or prongs 3 extending outwardly of the ring and at an angle with the plane thereof. Resting upon the looped portions of the fibers 1 is a cushioning member 4, consisting preferably of a disk of felt or similar material adapted both to give a cushioning effect and to be slowly permeated by oil or liquid polish. Resting

upon the cushioning member 4 is a metal cap 7, consisting preferably of a metal disk 55 having the central portion thereof raised above the plane of the outer portions thereof so as to form a chamber 8 between the said raised portion and the top of the cushioning member 4. Pivotal secured to the said 60 raised portion of the cap member and normally covering a central perforation therein is a cover 9 which is adapted by its pivotal mounting to be swung out of its normal position (as shown by dotted lines in Fig. 65 —2—) to permit access to the said chamber 8. The cushioning member 4 and the cap 7 which both covers and reinforces the same are simultaneously secured to the supporting member 2 by suitable fastening means, 70 such as the bolts 5.

When in use, the mop or brush is manipulated by a wooden handle 10 secured to the supporting member 2 of the mop by any suitable means, and preferably by the interchangeable clamping means shown and claimed in my copending application Serial No. 758,709, filed April 3, 1913. This fastening, as shown in Figs. —1— and —2— 75 consists essentially of a pair of metal clamping members 11 having their opposed faces concaved to match the curvature of the handle 10 and having recesses adapted to receive the said prongs or arms 3 between the respective clamping members 11 and the opposite sides of the handle 10, the said recesses being angularly disposed with respect to the common axis of the handle and the clamping members, so that the angle between the axis of the handle and the active 80 face of the brush or mop may be varied by inverting the position of the handle with respect to the prongs. By using such an interchangeable fastening, it will be evident from Fig. —1— that the handle may either be 85 disposed at such an angle as to avoid stooping on the part of the user of the mop, or at another angle (shown in dotted lines in Fig. —1—) permitting the mop to be used upon floors under radiators and various articles of low furniture.

Before using the mop, the swinging cover 9 may be swung out of alignment with the opening in the cap piece, thereby permitting the chamber 8 to be filled with a suitable oil or polish which will gradually per-

meate the oil-distributing disk 4 and the looped portions of the fibers in contact therewith. By thus interposing a thick layer of felt or other cushioning material I cause the oil or polish to work gradually through the fibers of the mop, thereby maintaining a continuous supply of the oil or polish for the active portions of the mop. The rate at which the oil or polish will thus be supplied to the fibers may be varied by using felt of various degrees of compression, but I preferably use a felt much less permeable by oil or polish than the fibers. Moreover, by making the contact between the cushioning and oil-distributing member 4 and the fibers of the mop with the looped portions of the latter I cause the oil or polish to be supplied simultaneously to both ends of each loop of fiber, instead of having a preponderance of the oil or polish upon the inner portions of the mop as has heretofore been customary with devices of this kind. I am, therefore, able to secure a much more even distribution of the liquid over the active face of the brush or mop than has been possible with the constructions heretofore in use. Moreover, by interposing the pervious member 4 between the fibers and the receptacle for the oil or polish, I prevent the latter from being fed to the active face of the brush or mop in such quantities as would spot or grease rugs or other textiles with which the fibers of my cleaning implement may come into contact.

It will be evident that any violent contact of the edges of the cap with furniture would tend to scratch or mar the same. I, therefore, preferably make the oil-distributing member 4 of somewhat larger diameter than the said cap, so that the projecting peripheral portion of the said member 4 will act as a cushion or bumper to avoid the damaging of furniture by contact with the edge portions of the head of the mop.

In assembling my cleaning implement, I preferably tighten the bolts 5 with sufficient force to compress the portion of the pervious member 4 covered by the cap 7, thereby causing the edge portions of the said member to bulge out above the top of the rim portions of the said cap, as shown in Figs. 1 and 3. However, I do not wish to be limited to this combination of a stiffening or reinforcing cap for the oil-distributing member and of a cushioning periphery of the latter extending both laterally and vertically beyond the edges of the former, nor to the precise fastening means or other details of the construction herein disclosed, it being obvious that the latter may be varied in many respects without departing from the spirit of my invention. Thus, instead of securing the annular member 2 to the cap member 7 by bolts passing through perforations in the member 2 and equipped

with nuts adjacent to the last-named member, the member 2 may be engaged by the hook ends of bolts equipped with nuts exposed upon the upper surface of the cap 7, as shown in Fig. 3.

I claim as my invention:—

1. A cleaning implement comprising a handle, an annular member secured thereto, a plurality of fibers looped over the said annular member, a disk of cushioning material bearing with one face against the looped portions of the said fibers, a cap member bearing against the other side of the said disk, and fastening means connecting the said members and extending through the said disk and clamping the fibers and the cushioning disk therebetween. 75 80

2. A cleaning implement comprising a handle, an annular member secured thereto, a plurality of fibers looped over the said annular member, a disk of pervious material bearing with one face against the looped portions of the said fibers, an apertured cap member bearing against the other side of the said disk, fastening means connecting the said members and clamping the fibers and the pervious disk therebetween, and a movable cover for the aperture in the said cap member, the portion of the cap member adjacent to the said aperture being 90 raised to form an oil receptacle between the said cap member and the said pervious disk. 95

3. A cleaning implement comprising a handle, an annular member secured thereto, a plurality of fibers looped over the said annular member, a disk of pervious material bearing with one face against the looped portions of the said fibers, an apertured cap member bearing against the other side of the said disk, fastening means connecting the said members and clamping the fibers and the pervious disk therebetween; and a movable cover for the aperture in the said cap member, the said aperture permitting 100 access to the upper face of the said pervious disk for the application of oil or polish thereto. 105 110

4. In a brush or mop, a handle, an annular member attached thereto, a brush member carried by the said annular member, an oil-distributing disk contacting with the brush member; a reinforcing disk for the said oil-distributing disk, the latter projecting laterally beyond the said reinforcing disk, the projecting portions adapted to act as a cushioning bumper for the brush or mop; and means for securing the said reinforcing and oil-distributing disks and the said brush member to the said annular member. 115 120 125

5. A cleaning implement including an annular member, a plurality of fibers looped over the same, a pervious member engaging loop portions of the said fibers, and a 130

cap member reinforcing the said pervious member, the said cap and pervious members being relatively so shaped as to afford a chamber therebetween for receiving oil.

5 6. A cleaning implement including an annular member, a plurality of fibers looped over the same, a pervious member engaging loop portions of the said fibers, and fastening means for securing the said fibers to
10 the pervious member, the latter being less

rapidly permeated by oil than the said fibers.

In testimony whereof I have signed my name in presence of two subscribing witnesses.

FRANK H. FRENCH.
